NORMAN L. SNOW, OF DETROIT, MICHIGAN, ASSIGNOR TO DIAMOND POWER SPECIALTY CORPORATION, OF DETROIT, MICHIGAN, A CORPORATION OF MICHIGAN

BOILER CLEANER

Application filed March 19, 1923. Serial No. 626,135.

This invention relates to boiler cleaners and particularly relates to boiler cleaners in which a dislodgment of soot from the boiler parts is effected by a discharge of steam or other fluid.

The invention has the nature of an improvement upon the construction disclosed in a copending application Serial Number 556,308, of Grant I. Rawson and said invention consists in the structural features and arrangement of parts hereinafter described and illustrated in the accompanying drawings, wherein:—

Figure 1 is a longitudinal sectional view showing the improved blower in its application to a tubular boiler of the Scotch Marine type;

Figure 2 is a somewhat similar view of the unit but drawn to a considerably larger scale;

Figure 3 is an end view of the rear flue sheet of the boiler showing the radial lines along which the cleaning jet impinges upon the flue sheet in the several selective positions of use of the unit;

Figure 3^a is a cross section of nozzle on 3^a—3^a of Figure 2;

Figure 4 is a view, partly in section and partly in elevation, showing an alternative construction of handle for the boiler cleaner and means associated therewith for determining the several rotatively spaced positions of use of said handle;

Figure 4^a is a transverse section of same;

Figure 5 is a sectional view similar to Figure 4 but showing another means for determining the selective positions of use of the blower.

In these views, the reference character 1 designates the fire tubes of a Scotch Marine boiler communicating at their ends respectively with the combustion chamber 2 and smoke box 3, the latter having the usual door 4 hinged as at 4''. The herein described blower is disposed within a fire tube 1^a which occupies preferably a substantially central position with respect to the remaining tubes. Said blower comprises a pipe 5 adapted to fit freely within the front portion of said tube 1^a. In the rear end of said pipe there is fixedly inserted a plug comprising the parts 6 and

6^a between which packing 6^b is compressed. The forward end of said pipe 5 projects slightly from the fire tube 1^a for engagement by a fitting 7 through which a steam supply connection is established from a pipe 8. 9 is a rod which passes freely through the fitting 7 and is rigidly connected to the tube 10 within the pipe 5, preferably, by inserting said rod a short distance within the tube and pinning the two together as indicated at 10^a. 10 The fitting 7 rigidly carries the sleeve 10^b which projects into the pipe 5, clearing the rod 9, and which within said pipe carries a slide bearing comprising the members 11 and 11^a inserted in said sleeve and packing 11^b compressed between said members. The tube 10 extends within the fire tube 1^a to the rear end portion thereof and terminally carries a steam discharge nozzle 12 normally housed within said end portion. 13 and 13^a designate coupling elements by which the nozzle is attached to the rear end of the tube 10. Within the pipe 5 and between the slide bearings 6, 6^a, 6^b and 11, 11^a, 11^b, a port 14 is formed in the tube 10 through which port, 75 steam (or other cleaning fluid), when admitted to the pipe 5 from the supply pipe 8, finds admission to the tube 10 to be conducted through the latter to the discharge nozzle 12. The space interval between the slide bearings 6, 6^a, 6^b and 11, 11^a, 11^b is sufficient to permit the port 14 to establish communication between the tube 10 and pipe 5 in all positions of sliding adjustment of said tube. To the front end of the rod 9 there is rigidly secured 80 a stem 15 forming a forward extension of said rod, said stem preferably having a lesser diameter than the rod 9 and having a screw-threaded engagement with said rod. To rigidly maintain this engagement, a lock nut 16 is engaged with the stem and bears firmly against the extremity of the rod. The forward end of the stem 15 is screw-threaded as indicated at 15^a for engagement with a plug 18, which plug is mounted in an elongated 85 tubular handle member 17 aligned with said stem. Adjacent its threaded end 15^a there is mounted fast upon the stem 15 as by a pin 19' a collar 19 which, in the retracted limiting position of the stem (shown in Figure 2), is 100

received in a slide bearing 20 integrally formed upon a spherical housing 21 secured to the door 4. The internal diameter of the bearing 20 is such that the handle member 17 may slide freely through said bearing. Said handle member is formed with a plurality of longitudinal grooves 22, all extending from the rear end of said handle member and varying in length in a predetermined relation and the handle 17 and plug 18 are both spaced sufficiently from the bearing 20 and collar 19 to form a circumferential groove 20'. Said grooves are circumferentially equi-distant, this being best seen in Figure 3. A screw 23 is radially mounted in the bearing 20, said screw having upon its inner end a pin 24 which projects within said bearing for selective engagement with the grooves 22 when the handle 17 is slidingly advanced through said bearing. The pin may be selectively placed in any one of the grooves by circumferential travel in the groove 20'. Thus said pin, in conjunction with the grooves 22, determines a plurality of rotatively varying positions in which the handle 17 may be rectilinearly advanced through the bearing 20 and determines corresponding positions of rectilinear advancement for the nozzle 12. An opening 25 in the door 4 permits advancing of the collar 19 and handle member 17 through said door and the sleeve 10^b accommodates the lock nut 16 during reciprocation of the nozzle and its actuating parts.

When the described blower is not in use the handle member 17 may be removed. Accidental shifting of the reciprocating parts, when the blower is in stored position, is prevented by engagement of a latch pin 26 in a socket 27 of the collar 19, said pin being urged into engagement with said collar by a supporting leaf spring 29. A cam lever 30 attached to said spring is encountered by the handle 17 as the same is screwed upon the stem 15 and thus provides for automatic disengagement of the pin 26 from the socket 27.

As will be evident from Figure 3, the circumferential spacing of the grooves 22 of the handle member is such that the corresponding impact lines upon the rear flue sheet 31 for the jets from the nozzle 12 will be most effective, said lines being indicated by the reference character 31^a. It is preferred to establish a slight angle between the radial planes of discharge of the two outlets of the nozzle 12, as is best indicated in Figure 3^a, the surface of the flue sheet being more effectively covered by the jets through this relation.

Thus, as is shown in Figure 3, for the twelve rotative positions of adjustment of the handle, there are twelve lines of impact upon the rear flue sheet for one of the jets from the nozzle, as indicated by A, B, C, etc. and twelve corresponding lines of impact for the other jet, as indicated at A', B', C', etc.,

the lines of impact for one of the jets falling substantially midway between those for the other.

In the use of the described blower, the operator engages any one of the grooves 22 with the pin 24 and then advances the handle member 17 and thereby the nozzle 12 so far as the length of the engaged groove will permit. The nozzle is so positioned circumferentially with respect to the various grooves that the extent of longitudinal travel afforded the nozzle in each of the selected rotative positions of the handle permits the corresponding line of impact of the jets to extend to the outer margin of the rear flue sheet. After completing each blowing advancement of the nozzle, the operator retracts the handle and nozzle to align the pin 24 with the groove 20', in which position the handle is rotatively actuatable to engage the next adjacent groove 22 with the pin 24. The handle and nozzle are then again advanced so far as the length of the engaged groove will permit. This is continued until a blowing advancement of the nozzle has been effected in each of the selective rotative positions thereof. The nozzle will then have applied jets to the rear flue sheet along each of the impact lines indicated at 31^a in Figure 3. These impact lines are so selected that a thorough discharge of the cleaning fluid through all of the fire tubes will be produced by the successive impacts of jets along said lines.

In that form of the invention disclosed in Figures 4 and 4^a, the selective rotatively varying distances of the nozzles are adapted to be established by the use of an elongated handle member 34 of octagonal cross section, an opening 35 of corresponding shape being formed in a guide plate 36 which is secured to the door 4'. In this form of the invention, the engagement of the handle member with the stationary guide member carried by the door restrains the handle member and consequently the nozzle from rotation in any except a fully retracted position of the handle member in which position the handle member 34 is moved out of engagement with the opening 35. In this case there is no provision for varying the extent of reciprocation and the circumferential advance of the nozzle from one to another of its positions of use is a constant.

In the construction shown in Figure 5, the reciprocating handle member 37 is of hexagonal cross section and is engageable with an opening 38 in a guide plate 39, the margin of which is formed with twelve equi-distant angular depressions for engagement by the angles of the member 37. Thus, there are established twelve selective positions of use for the corresponding nozzle. Obviously, the number of selective positions of use can be predetermined to suit any requirements by giving the actuating bar and the correspond-

ing opening in the stationary guide member the proper polygonal form. The term "rotative" as employed in this specification and in the appended claims is considered to designate the capacity for turning through either a fractional or entire revolution or a plurality of revolutions.

What I claim as my invention is:—

1. In combination with a boiler having a tube sheet and a plurality of tubes, of a nozzle normally lying within one of said tubes, said nozzle having a discharge port adapted when the nozzle is projected from said tube to discharge cleaning fluid toward said tube sheet and being reciprocatory in the direction of the tubes to effect a projection of said nozzle from said tube, said nozzle also being adapted for rotation through a plurality of predetermined increments to vary the angle of said discharge port to said tube, means for reciprocating said nozzle to project the same from the said tube, and means preventing rotation of the nozzle when it is in said projected position. 70
2. The combination with a boiler having a plurality of spaced fire tubes, of a cleaner element, said element having a rearwardly discharging nozzle and being disposed in one of said tubes and movable axially thereof, means for reciprocating said element, means permitting rotation of said element when it is in a predetermined position with relation to its enclosing tube, means for limiting the reciprocation of the element to a predetermined series of angular positions with respect to said tube, and means for preventing rotation of the cleaner during reciprocation, said nozzle being arranged to clean a given group of tubes corresponding to its angular position, each time it is projected from its enclosing tube. 75
3. The combination with a boiler having a plurality of spaced fire tubes, of a cleaner element, said element having a rearwardly discharging nozzle and being disposed in one of said tubes and movable axially thereof, means for reciprocating said element, means permitting rotation of said element when it is in a predetermined position with relation to its enclosing tube, means for limiting the reciprocation of the element to a predetermined series of angular positions with respect to said tube, means for preventing rotation of the cleaner during reciprocation, and means for varying the reciprocatory stroke of the element in accordance with the remoteness of the tubes, said nozzle being arranged to clean a given group of tubes corresponding to its angular position each time it is projected from its enclosing tube. 80
4. The combination with a boiler having a tube, of a cleaner for the said boiler, the said cleaner including a cleaner element normally housed within the said tube, means for rotating said element and for longitudinally moving the element to cause the same to project beyond the said tube, and means for variably limiting the longitudinal movement of the element dependent upon the rotative position of said element with respect to said tube. 85
5. The combination with a boiler having a plurality of tubes, of a nozzle adapted to discharge a jet of fluid for cleaning a plurality of said tubes, means for reciprocating said nozzle in a plurality of predetermined positions to direct the jet to effect cleaning of a group of said tubes on either side of said nozzle in each of said positions, means for rotating the nozzle to move the same from one to another of said predetermined positions and means preventing rotation of the nozzle during reciprocation thereof. 90
6. The combination with a boiler having a plurality of tubes, of a rotative and reciprocatory nozzle adapted to discharge a jet of fluid for cleaning the tubes lying in successive radial zones, means for reciprocating said nozzle to direct the jet to clean the tubes of one of said zones, means for rotating the nozzle to advance same to a position to clean another of said zones and means for preventing rotation of the nozzle during reciprocation thereof. 95
7. The combination with a boiler having a tube, of a cleaner for the said boiler, the said cleaner including a cleaner element normally housed within the said tube, means for rotating said element and for longitudinally moving the element to cause the same to project beyond the said tube, and means for variably limiting the longitudinal movement of the element dependent upon the rotative position of said element with respect to said tube. 100
8. The method of cleaning a plurality of tubes having their ends arranged in a predetermined relation with respect to each other which consists in discharging a jet of cleaning fluid at an angle toward the said tube ends, varying the distance of the source of said jet from the said tube ends to cause the jet to successively clean a predetermined series of said tubes and limiting the travel of said jet from said tube ends in dependence upon the length of the series of tubes being cleaned. 110
9. The method of cleaning a plurality of tubes having their ends arranged in a single plane and in lines extending radially from a source of cleaning fluid which consists in discharging a jet of cleaning fluid at an angle from the source toward the plane of the tube ends, varying the distance of the said source from the plane of the tube ends while preventing rotation of the jet to cause the jet to 115
10. The method of cleaning a plurality of tubes having their ends arranged in a single plane and in lines extending radially from a source of cleaning fluid which consists in discharging a jet of cleaning fluid at an angle from the source toward the plane of the tube ends, varying the distance of the said source from the plane of the tube ends while preventing rotation of the jet to cause the jet to 120
11. The method of cleaning a plurality of tubes having their ends arranged in a single plane and in lines extending radially from a source of cleaning fluid which consists in discharging a jet of cleaning fluid at an angle from the source toward the plane of the tube ends, varying the distance of the said source from the plane of the tube ends while preventing rotation of the jet to cause the jet to 125
12. The method of cleaning a plurality of tubes having their ends arranged in a single plane and in lines extending radially from a source of cleaning fluid which consists in discharging a jet of cleaning fluid at an angle from the source toward the plane of the tube ends, varying the distance of the said source from the plane of the tube ends while preventing rotation of the jet to cause the jet to 130

clean all of the tubes in one of the radial lines and subsequently rotating the jet and again varying its distance from the plane of the tube ends to cause the jet to clean the tubes in another radial line.

5 In testimony whereof I affix my signature.
